(57) **CLAIM**

The ornamental design for a saddle and water bottle as shown and described.

DESCRIPTION

FIG. 1 is a perspective view of a saddle and water bottle as assembled;

FIG. 2 is a front elevation view, thereof;

FIG. 3 is a rear elevation view, thereof;

FIG. 4 is a left side elevation view, thereof;

FIG. 5 is a right side elevation view, thereof;

FIG. 6 is a top plan view, thereof;

FIG. 7 is a bottom plan view, thereof;

FIG. 8 is a perspective view of the water bottle of the saddle and water bottle of FIG. 1, disassembled;

FIG. 9 is a front elevation view, thereof;

FIG. 10 is a rear elevation view, thereof;

FIG. 11 is a left side elevation, thereof;

FIG. 12 is a right side elevation view, thereof;

FIG. 13 is a top plan view, thereof;

FIG. 14 is a bottom plan view, thereof;

FIG. 15 is a perspective view of the saddle of the saddle and water bottle of FIG. 1, disassembled;

FIG. 16 is a front elevation view, thereof;

FIG. 17 is a rear elevation view, thereof;

FIG. 18 is a left side elevation, thereof;

FIG. 19 is a right side elevation view, thereof;

FIG. 20 is a top plan view, thereof; and,

FIG. 21 is a bottom plan view, thereof.
